UNITED STATES PATENT OFFICE.

FREDERICK A. COLEMAN, OF CLEVELAND, OHIO, ASSIGNOR, BY MESNE ASSIGNMENTS,
TO CARL W. SCHAEFER, OF CLEVELAND, OHIO.

ELECTRIC CORE OVEN.

Application filed April 28, 1923. Serial No. 635,378.

To all whom it may concern:

Be it known that I, FREDERICK A. COLEMAN, a citizen of the United States, residing at Cleveland, in the county of Cuyahoga and State of Ohio, have invented a certain new and useful Improvement in an Electric Core Oven, of which the following is a full, clear, and exact description, reference being had to the accompanying drawings.

10 This invention relates to electric ovens such, for instance, as are used for baking cores.

The general object of the invention is the provision of an extremely efficient heating oven. Walls of an electrically heated oven should be made of a material high in heat resisting properties and at the same time of sufficient strength to insure a rigid structure. A preferred way to accomplish this is to 20 construct the oven walls of refractory material and brace these walls by metal frames. However, in so doing, it has been found that either the walls are compressed against each other at their juncture resulting in crumbling 25 effects, imperfect joints, etc., or the efficiency of the oven is greatly reduced through the wasteful conduction of heat from the ovens by the frame members or through bolts connecting such members.

30 One of the objects of my invention is to eliminate the usual bolts and stays for holding the structure together and which extend through the refractory walls. One of the problems solved by my invention is of bracing each of the individual wall members by a metal frame in such a way that no part of the metal framework is exposed to the heat within the oven.

Another object is the provision of a compact and durable heating element in a core oven that may be protected against fouling by the material to be heated and at the same time function at the highest degree of efficiency, the protective device serving to better distribute the heat to all parts of the oven. In cooperation with the heating element and protective device, I have also provided a ventilating shaft system designed to distribute air currents within the chamber 50 in a novel and very effective manner.

A further object is the provision of a safety cutout for the high tension electric circuit, generally used in such ovens, which prevents the operator from incurring

physical harm by causing opening of the 55 heating circuit whenever the elements are moved to accessible position.

Other objects will become apparent in the following description of my invention which refers to the accompanying drawings, and 60 its essential characteristics are summarized in the claims.

In the drawings, Fig. 1 illustrates the preferred form of my invention and is in the nature of a longitudinal central section 65 through an entire oven; Fig. 2 is a sectional plan taken along the line 2—2 of Fig. 1 showing the drawer supporting the heating elements; Fig. 3 is a vertical section through the oven as indicated at 3—3 of Fig. 1; Fig. 70 4 is a plan view of the frame comprising the heating element support showing all but one of the elements removed therefrom; Fig. 5 is a rear elevation of a portion of the oven 75 wall showing the safety cutout device; Fig. 6 is a sectional plan through the cutout device taken along line 6—6 of Fig. 5; Fig. 7 is in the nature of a fragmentary perspective 80 illustrating the front, side and roof of the furnace and is broken away to show the manner in which the frame members retain and support the body of the walls and roof; Fig. 8 is a wiring diagram showing the electrical connection of the heating elements 85 with the current supply and the protective cutout switch.

Referring to the various parts by numbers, in Figs. 1, 2 and 3, 1 designates the oven in general, which is made up of side, front and rear walls, designated 10, 11 and 90 12, and ceiling and floor wall members 13 and 14, which are suitably retained and braced against each other by a skeleton frame work of metal channel and angle members to be later described.

95 It has been found convenient to use in this oven the system of drawers for holding the material to be heated such as shown at 20, consisting of a lattice framework suitably braced, and being provided with rollers 100 21 mounted on a through shaft 22, and a head portion 23. Suitably braced heat resisting material substantially closes the openings in the front wall 11 of the oven through which the drawers are inserted. 105 The lattice framework carries the material to be baked or heated. The drawers are supported within the oven by a frame 25 and

are adapted to be withdrawn from the oven by suitable drawer engaging mechanism 30. Any convenient mechanism might be employed for this purpose. I have shown a 5 depending beam carrying suitable drawer engaging members supported by a trolley 31, mounted on rollers 32 which are adapted to rest on channel rail members 33 rigidly supported by the oven frame.

10 The heating elements are carried by a drawer similar in some respects to the drawer 20. This drawer is mounted upon rollers and may be removed from the oven for repairs or cleaning in much the same 15 manner as the drawers 20. This structure will be later described more in detail.

Referring to the walls, top and floor structure, as shown in Figs. 1, 2, 3 and 7, it will be seen that I have made the walls, 20 top and floor of slabs of refractory material such as fire brick or similar substance and have assembled the slabs or sections in the following manner:

The side walls, 10, Fig. 2, are contained 25 within a frame work comprising vertical and horizontal angle members 61, 62, 63 and 64. The rear wall is suitably held in position by vertical angle members 65 and horizontal angle members 67. Figs. 1 and 3 30 show the roof 13 as retained by a rectangular frame structure comprising longitudinal angle members 68 and transverse members 69 and 70. The front wall portion 11 is in the nature of a grille, comprising upright 35 channel frame members 80 and cross bars formed of channels 81. These bars and uprights, it will be noted, support merely their own weight, hence a comparatively light frame is used which will conduct and radiate 40 only an insignificant quantity of heat. The flanges of all these channels extend inwardly and are completely filled with heat resisting material as indicated at 82. The cross bars form openings wherethrough the drawers 45 are inserted. A fabricated T bar 66 is secured to the uprights 61 in such a manner as to overlie the members 80 and retain the drawer frame in place.

It will be noted that the walls 10 and 12, 50 and the roof 13, have projections 14, 15 and 16 that extend over the inwardly projecting flanges of the angle members that form the frame, thus closing the corners against heat 55 radiation by conductance through the angle members. Where it is inconvenient to use such projections as at the juncture of the side walls and the roof, the flange of the angle stops short of projecting into the oven and the resulting crevice between the 60 wall and roof is filled with refractory heat resisting material as at 64. The whole structure may be conveniently tied together at the corners by gusset plates 71 and 72 as shown in Fig. 7.

65 The car containing the heating elements,

the air inlet ventilating shafts and protective baffle plates in the form I prefer and have found satisfactory will now be described.

The car frame, as shown in Fig. 4, is 70 made up of side angle members 91, and front and rear angle members 92 and 93, respectively. A refractory closing block 95 is interposed between the frame member 92 and a plate 96; suitable bolts, not shown, 75 extending from the frame member to the plate will hold the structure together. The refractory material substantially closes the lowermost opening in the grid-like structure forming the front wall when the car 80 is in position and a suitable angle member 97, bolted to the upright frame members 61, holds the car in place. Mounted on the car frame members are rollers 85 supported in brackets 86 on the frame members 91, which 85 rest on rails 87 in the form of channel members imbedded in the floor 14 as shown in Fig. 3.

A pair of tubes 100, open at their outer end and provided with dampers 101, are 90 suitably carried on the plate 96 at one end. These tubes extend within the oven beneath the car frame and are secured by means of U-bolts 102 to the frame member 93 at their rear end. A refractory plug closes this rear 95 end of each tube. A long slot uniformly tapered toward the rear is cut into the tubes as shown at 104 and is cut along an axial plane inclined 45 degrees from the vertical. This is for directing the flow of air toward 100 the central portion of the oven, it being found advantageous to so direct the air within the chamber to prevent excessive cooling along the side walls while not sufficiently ventilating the oven at the center. The angle of direction may be changed if necessary by rotating the tubes, thus affording complete control of the air flow within this 105 chamber.

The heating elements comprise coils of 110 wire 110, wound upon suitable cylinders of insulating material 111, which are in turn supported by bolts or rods 112 and 113 insulatingly supported at their ends by channels 115, best shown in Figs. 1, 3 and 4. The 115 resistance heating strips or wires 110 are fastened directly to the bolts 112 and 113 at their ends and convenient bus bars 120, 121 and 122 serve to carry the electric current to the wires through the bolts 112 and 120 113 as shown in Fig. 4.

Resting upon the channel members 115 and suitably spaced apart from both the channels and from each other by annular spacing members 125 are baffle plates 126 125 and 127. In Figs. 2 and 3, it will be noted that these baffle plates are so perforated that all the holes in the lower plate are offset from those in the upper plate, this serving to better distribute the air currents and pre- 130

vent material from the core carrying drawers positioned above from falling upon and fouling the heating elements.

Bridging the channel or rail members 33 on the top of the oven is shown a plate 34 which supports a system of ventilating pipes 35, 36 and 37, which connect with the interior of the oven through the roof 13. It has been found convenient to provide each 10 of the smaller pipes 36 and 37 with dampers 38 and 39, as well as so providing the central common ventilating shaft or chimney 35.

A bracket 130 formed of insulating material and secured to the rearmost frame member of the car supports the bus bars at their rearwardly extending ends and it will be seen that they project through the rear wall 12 into a boxlike structure shown in Figs. 1, 5 and 6 which carries a cutout switch and 20 cable terminals.

In the diagram Fig. 8, A, B, C, D, E and F, indicate the heating coils. In order to balance the circuit two of the coils are shunted across each phase of the circuit. 25 The coils A and D bridge the bus bars 121 and 122, the coils C and F bridge the bars 120 and 122 while the remaining coils B and E connect the combination of bars 120 and 121.

30 The universal circuit breaker 155 is so arranged as to disconnect all the feed wires simultaneously from the current supply, this being indicated as a delta connection three phase circuit 156. The circuit 152 in which 35 is the safety switch 140, the solenoid 159, for operating the switch 155 and a manually controlled switch 158, is shunted across one phase of the supply and draws only a small amount of current.

40 In order to heat the oven the switch 158 is first closed, thus through the medium of the solenoid 159 closing the switch 155. The movement of the bar 150, occasioned by thus closing the circuit 152, is only sufficient to 45 close the main circuit. However, should an excessive amount of current be drawn into the circuit 152, the bar 160 moves the toggle joint 161 over a dead center and a convenient spring 162 acts to break the heating circuit. 50 This may also be done by opening either of the switches 140 or 158, the former of which is part of a safety device which will be later described.

55 The terminal concealing cabinet 132 is formed of a substance that is non-conductive of both heat and electricity, such for instance as asbestos board. Part of the structure is removable. The stationary portion 133 is built into a rectangular hole in 60 the wall 12 and is a framework having front, and rear walls 135 and 136 joined by side walls 137 and web members 138. The safety switch 140 is contained in one of the spaces between the webs 138 and the 65 walls 137. The removable portion of the

cabinet designated 134 is in the nature of an open box having a rear wall 141, side, top and bottom walls 142, and suitable attaching angle members 145, whereby it may be secured to the rear wall frame members 146. 70 The lower wall 142 is slotted at 146 for admitting the cables 120^a, 121^a and 122^a, within the box and at 147 for the cables 152. A block 147 is secured to the rearward face of the wall 141 which when the cover box is 75 attached to the oven frame pushes inwardly on a button pin 150 of the switch 140. This pin is carried at its inner end by a contact block (ordinarily held by suitable springs against the outer wall of the switch box and away from the spring contact plates 158,) thereby closing the separate circuit 152.

In this manner, I have provided a guard whereby the high tension wires or cables leading to the bus bars may be effectively 80 enclosed and protected until it is found necessary to withdraw the heating elements from the oven. The guard box 134 may be removed to allow access to the cable terminals and this removal automatically 85 opens the separate circuit 152, which in turn operates the circuit breaker 155. Thus in order to get at the oven, it is first necessary to remove the box or guard which opens the circuit. An extremely efficient safety device 90 and terminal housing is thus provided.

Having thus described my invention, I claim:—

1. In an electrically heated core oven, an 100 electric heating element, wall, ceiling and floor members formed of heat resisting material and a contiguous outer metal skeleton individually supporting each of said members.

2. In an electrical oven, an electric heating element, a metal frame work comprising a series of joined rectangular frames, each adapted to independently support a wall slab of refractory material, all parts of 110 said frame work stopping short of entering the chamber formed by the slabs.

3. In a core oven having a heating element and side, top and bottom walls, a heat 115 resisting slab forming the body of one of the walls, a continuous metal frame embracing the perimeter of such slab and having flanges lying along the exposed surface thereof, another slab placed at right angles to the first named slab, and a projection on the inner surface thereof adjacent to the perimetral flange of said first named slab, whereby a rabbeted joint is formed at the juncture of the slabs.

4. In combination in a core oven having 120 a heating element, a composition wall, a frame adapted to closely embrace the periphery thereof and overlie the margin, a second wall having a similar frame placed at right angles to the first named wall and 125 overlying the peripheral edge thereof, a 130

projection rising from the last named wall in abutting relation to the inner margin of the first named wall and means whereby a frame member of one wall is rigidly joined to a corresponding frame member of the other.

5. In combination, in an electric oven, an electric heating element, wall slabs placed at right angles to each other, the marginal edge of one overlapping the peripheral edge of the other, a frame member interposed between the said edges and extending at right angles along the marginal edge of the last named wall member, an angular frame member of the last named wall member interposed between the peripheral edge of the last named wall member and the margin of the first named wall member, means for rigidly securing the frame members one to the other and a rib on the first named wall adjacent the juncture of the walls whereby a corner closure is formed.

6. In combination with a core oven having a heating element, side, top and bottom walls, a heat resisting slab forming the body of one of the walls, a continuous metal frame embracing the peripheral edges of the slab and having inturned flanges extending along a surface of the slab, a second slab set at right angles to the first named slab, and an interposing frame member partially covering the peripheral edge of the second slab and having inturned flanges extending along a surface thereof, means for securing the frame members together and means for closing the crevices formed between the peripheral edge of the first named slab and the adjacent end of a second slab.

7. In combination with an oven, having refractory walls, floor and ceiling, a drawer supported by the floor, electric heating elements and ventilating tubes carried by the drawer and air baffle plates surmounting the entire structure whereby the heating elements are protected from above.

8. In a core oven having heat resisting walls and a heating element, a plurality of perforated air baffle plates mounted above said element, all the perforations in one of the plates being offset from the perforations in the others, means for holding the plates in spaced relation to each other, and means cooperating with said last named means for mounting the plates above the heating element whereby a protection for the elements and a heat distributor is provided.

9. In an electrically heated oven a removable drawer, an electric heating element within the drawer, a drawer wall, a plurality of ventilating tubes carried by the drawer and means consisting of converging slots in the walls of the tubes whereby the air entering the tubes is evenly distributed throughout their entire length and is directed toward the center of the oven.

10. In a core oven having heat resisting walls and a heating element, means for ventilating the oven consisting of a plurality of air shafts entering the oven at its base, said air shafts having slots in their walls converging toward the entrance of the shaft, and regulatable means for allowing air to pass out of the roof of the oven.

In testimony whereof, I hereunto affix my signature.

FREDERICK A. COLEMAN.
